STOP-MOTION FOR FULL FASHIONED
KNITTING MACHINES

Basil H. Lane, Greeneville, Tenn., assignor of one-third to Robert Fulton Morgan and one-third to James Hosiery Mills, a corporation of Tennessee, both of Greeneville, Tenn.

Application January 18, 1951, Serial No. 206,614

10 Claims. (Cl. 66—157)

1

This invention relates to full fashioned hosiery knitting machines and more especially to an improved stop motion mechanism or safety switch, the primary object of which is to provide means for automatically stopping the knitting machine upon failure of the usual welt hooks associated with a welt turner moving into and out of operative position relative to the vertically movable needles in proper timed relation.

As is well known to those familiar with the art, a welt turner is provided with a plurality of spaced welt hooks which move into position between certain spaced sinkers, there being one of these welt hooks for every other needle in each section of a full fashioned hosiery knitting machine. Certain cam means are provided which cause the welt hooks to move downwardly into engagement with the beards of alternate needles as these needles are lowered and subsequently hold the beards in closed position so that alternate loops will be withdrawn over the tops of the needles.

Then, as the loops are withdrawn from the tops of the needles as a result of the needles moving downwardly beneath the sinkers, the welt hooks move downwardly into the loops previously cast from the corresponding needles and thus support the knitted fabric and resiliently pull the fabric outwardly away from the sinkers during knitting of subsequent stitches. A suitable welt rod is manually inserted in suitable spring loaded members disposed adjacent opposed sides of the knitted fabric as it is drawn outwardly away from the sinkers and, after a predetermined number of courses have been knitted, the welt hooks again move inwardly toward and between the sinkers as the corresponding needles assume a lower position and then these needles move upwardly to pass between the loops previously transferred to the welt hooks to take the loops therefrom and following which the welt hooks move upwardly with the needles and then inwardly relative to the sinkers and away from the beards of the needles and are finally moved upwardly to inoperative position to complete the cycle in the operation of the welt hooks.

Now, knitting machines of this type are provided with a locking cam mounted on the welt turner cam shaft which transmits movement to the welt turner and this welt cam has a pair of diametrically opposed notches therein which are adapted to be engaged by a roller on the free end of a pivoted arm, the position of these notches in the lock cam relative to the arm denoting that the proper sequence of the welt turner and the needles may be assured. However, there are in-

stances when the lock cam may not be properly positioned at the time the welt turner moves into operative position with the result that the timing of the movement of the needles and the sinkers will not correspond properly to the timing of the movement of the welt turner into and out of operative position. This results, in many instances, in a substantial number of the sinkers being broken or damaged as well as the beards on a substantial number of the needles being torn from the needles and thus requiring a considerable down time of the machine and expense in replacement of the needles, sinkers and dividers.

It is therefore, another object of this invention to overcome such defects by providing an improved stop motion comprising a pair of plungers which are adapted to be engaged by the arm having the roller on the free end thereof which engages said lock cam and having means connected to one of the plungers for operating a switch interposed in the circuit to the electric motor which drives the knitting machine and the other of the plungers having means associated therewith for releasing the first-named plunger from a suitable locking device or latch as the roller on said arm drops into the next notch in said lock cam and, in the event of this locking device not being positioned in a locking position, upon the arm moving upwardly out of engagement with the plungers twice in succession, the switch will then be operated to interrupt the flow of electrical energy to the electric motor.

In other words, in advance of each period in which the corresponding notch in the locking cam moves out of engagement with said roller, means on the automatic shaft which control various operations of the machine, such as its speed, narrowing fingers, friction releases etc., cause the latch means to move into latching position and, as the locking cam rotates to elevate said arm, only one of the plungers may move upwardly because of the other plunger being held downwardly by said latch means and, before the roller on said arm drops into the next succeeding notch in said lock cam, there is provided means engageable by said plunger, which had been caused to move upwardly, for releasing said latch means from the lower portion of the other of the plungers and, in the event that the latch means is not again positioned in latching position and the cam rotates to where the roller again starts to move out of the first-named notch, both of the plungers will move upwardly to thus operate a switch mechanism for stopping the motor which drives the machine.

Some of the objects of the invention having

been stated, other objects will appear as the description proceeds when taken in connection with the accompanying drawings, in which—

Figure 1 is a transverse vertical sectional view through a typical full fashioned hosiery knitting machine showing the automatic welt turning attachment in association therewith and also showing the improved stop motion in association therewith;

Figure 2 is an enlarged fragmentary vertical sectional view taken substantially along the line 2—2 in Figure 1;

Figure 3 is an enlarged fragmentary top plan view with parts broken away and looking substantially along the line 3—3 in Figure 2;

Figure 4 is an enlarged elevation of the improved stop motion looking at the back of the plate which supports the same and substantially along the line 4—4 in Figure 3 with various of associated parts being shown in cross section;

Figure 5 is an enlarged view similar to Figure 4 but showing the parts in a different position;

Figure 6 is a vertical sectional view taken substantially along the line 6—6 in Figure 5;

Figure 7 is a view similar to Figures 4 and 5 but showing the parts in still another position;

Figure 8 is a vertical sectional view taken substantially along the line 8—8 in Figure 5.

Referring more specifically to the drawings, the numeral 10 broadly designates the frame of the machine which includes a plurality of spaced upright transverse frame members 11, only one of which is shown in Figure 1 and these frame members are joined by front and rear bottom rails 12 and 13, respectively. The upper portion of the frame 10 supports a rotatable take-up shaft 15 rearwardly of which is disposed a table frame member 16 and spaced rearwardly of the table frame member 16 is a horizontally disposed and longitudinally extending sinker head rail 17 which supports a conventional sinker bed. The front ends of the sinker bed has conventional sinkers 18 slidably mounted therein between which are the usual dividers, not shown. Vertically movable beard needles 22 are adapted to pass between the sinkers and the dividers and cooperate with the same in forming stitches.

The lower ends of the needles 22 are attached to a needle bar 24 which is operated in a conventional manner by a conventional mechanism, not shown. An electric motor 25, which is only shown schematically in Figure 4, transmits rotation to a conventional main cam shaft 26 through conventional intervening connections not shown, the cam shaft 26 being suitably supported for rotation in the frame 10.

It might be stated that this main cam shaft 26 is instrumental in transmitting vertical movement to the needle bar 24 and the corresponding needles 22 as well as the sinkers and the dividers on the sinker bed 20. The manner of operation of the main cam shaft 26 and intervening connections, not shown, for operating the sinkers and the dividers is well known to those familiar with the art and a description thereof is thus deemed unnecessary. The flat or full fashioned hosiery knitting machine shown in the present drawings is of a type substantially as is shown in a patent to Lieberknecht, No. 2,195,872 of April 2, 1940, and in a patent to Zesch, No. 2,432,108 of December 9, 1947, and substantially as manufactured by Karl Lieberknecht, Inc., Reading, Pennsylvania.

Suitably supported on the rear of each of the transverse frame members 11 of the knitting ma-

chine frame 10 is a top galley frame member designated broadly at 30 and which includes an upstanding portion 31 having a forwardly extending portion 32 at the upper end thereof. This forwardly extending portion 32 of the galley frame member 30 supports a horizontally disposed welt turner cam shaft 33 for rotation thereon and this welt turner cam shaft 33 has a suitable cam means, not shown, associated therewith for imparting vertical movement to a welt turner broadly designated at 35.

The welt turner 35 includes an upper substantially horizontally disposed forwardly and rearwardly extending arm 36 which is pivotally mounted at its rear end on a shaft 37 oscillatably mounted in suitable bearing blocks 40 which are, in turn, suitably secured to the upper surfaces of a plurality of the upper galley frame portions 31. The front end of the arm 36 has a substantially vertically disposed and downwardly extending welt turning arm 41 pivotally connected thereto as at 42, and which is normally urged outwardly or in a counter-clockwise direction in Figure 1 by a suitable conventional spring means not shown. The lower end of the vertically disposed welt turner arm 41 of the welt turner 35 has a conventional welt hook supporting bar 43 suitably secured thereto in which a plurality of spaced welt hooks 44 are suitably secured and which extend downwardly therefrom.

As is well known to those familiar with the art, these welt hooks are caused, through conventional pattern controlled clutch means, not shown, on the welt turner cam shaft 33, to move downwardly between certain of the spaced sinkers as alternate needles, which correspond to these welt hooks 44, move upwardly above the sinkers so the loops on these particular needles may be transferred from the needles to the welt hooks in the course of a welt turning operation.

It is thus seen that the operation of the welt turner 35 must be accurately timed relative to movement of the sinkers and the needles as this movement is transmitted thereto from the main cam shaft 26. The welt turner cam shaft 33 is driven through suitable connections to the main cam shaft 26, these connections including a relatively large beveled gear 50 rotatably mounted on the cam shaft 26 and which meshes with a relatively small beveled gear 51 fixed on the lower end of a rearwardly and upwardly extending angularly disposed shaft 52, this shaft 52 being rotatably mounted in suitable bearing blocks 53 and 54 which are suitably secured to the lower frame member 11. The upper end of the shaft 52 also has a beveled gear 56 fixed thereon which meshes with a beveled gear 57 fixedly mounted on a horizontally disposed shaft 60 which extends longitudinally of the machine and at the rear end thereof. This shaft 60 transmits rotation to an upwardly and forwardly extending angularly disposed shaft 61 through suitable gearing not shown, and the upper end of the shaft 61 also has suitable gearing thereon for transmitting rotation to the welt turner cam shaft 33.

The cam shaft 26 has a conventional clutch means associated therewith, not shown, which is pattern controlled for intermittently driving the gear 50 and shaft 33. The control means for the welt turner 35 and the welt turner cam shaft 33 may be substantially as shown in Lieberknecht Patent No. 2,183,575 of December 19, 1939, and a further description thereof is deemed unnecessary.

Each of the transverse frame members 11 also

has an upwardly projecting rear portion 65 which is disposed forwardly of the upper galley frame 30, in the upper end of which a horizontally disposed automatic shaft 66 is rotatably mounted and this shaft 66 being driven intermittently, in a step-by-step manner, through suitable well known pattern mechanisms and connections, by the cam shaft 26, as shown in Figure 5 of said Zesch patent, so as to operate in correct timed relation to the operation of the needles 22, the sinkers and the dividers. This automatic shaft 66 is instrumental in providing the pattern for determining the operation of such devices as the widening and narrowing mechanisms, picot attachments, lace attachments and the like all of which have been omitted from the drawings since they are not pertinent to the present invention.

It will be observed that the automatic shaft 66 is usually provided with a plurality of pattern disks or segment disks having segments thereon for controlling the usual patterning operations of the machine, and in this instance, a similar segment or pattern disk 70 is shown fixed on the shaft 66 and which has first and second spaced segments or cam members 71 and 72 thereon and which are suitably secured thereto as by screws 73. The spacing of the segments 71 and 72 is, of course, dependent upon the particular patterning otherwise controlled by the automatic shaft 66.

Now, in setting up the machine preparatory to knitting a certain type of article, there is provided a conventional locking disk or cam 75 which is provided with a pair of diametrically opposed first and second notches 76 and 77, respectively. This locking disk or cam 75 is adjustably secured on the welt turner cam shaft 33 by a suitable set screw 80 and, upon the various parts of the knitting machine being adjusted so as to operate in proper sequence as heretofore described, the locking disk 75 is positioned so that a roller 81 rotatably mounted on the free end of a locking arm 82 will drop into one or the other of the notches 76 or 77 as the arm 41 of the welt turner 35 moves the corresponding welt hooks 44 into operative position for turning the welt of a full fashioned stocking.

The shaft 33 and the corresponding locking disk or cam 75 then remain stationary during the forming of the welt and upon the welt forming operation being completed, the arm 41 then operates in a well known manner to cause the welt hooks 44 to again deposit the loops thereon onto the corresponding needles and to move upwardly to inoperative position and, during said last operation, a half revolution is imparted to the locking disk or cam 75, upon completion of which the roller 81 will drop into the other of the notches 76 or 77.

It will be observed in Figure 1 that the rear end of the locking arm 82 is oscillatably mounted on the shaft 37 and this locking arm 82 and the corresponding roller 81 have no function other than that of determining whether or not the position of the shaft 33 is correct relative to the position of the various other knitting instrumentalities.

The various parts of the machine heretofore described, other than the special segment disk 70 and its segments 71 and 72 are conventional parts of a full fashioned or flat knitting machine having a welt turning attachment and it is with these parts that the present invention is particularly adapted to be associated.

Referring to Figure 3, it is clearly shown that

the forwardly extending arm or portion 32 of the upper guide frame member 30 is off-set to thus form a shoulder 32a at the rear of shaft 33 and on which a vertically disposed plate or bracket 91 of an improved stop motion control apparatus broadly designated at 92 is secured as by screws 93.

It will be observed in Figures 2, 4, 5 and 7 that the free end of the plate or bracket 91 terminates adjacent the locking disk or cam 75. This plate or bracket 91 has a pair of vertically spaced guide blocks 95 and 96 secured thereto as by screws 97 and 98 respectively (Figures 4 and 6). A pair of horizontally spaced vertically disposed plungers, namely, a first plunger 101 and a second plunger 102 are mounted for vertical sliding movement in the guide blocks 95 and 96 and are confined therein by suitable plates 103 and 104 which are secured to the rear faces of the respective guide blocks 95 and 96 by the screws 97 and 98 heretofore described.

The upper ends of the vertically movable first and second plungers 101 and 102 are provided with respective adjustment screws 105 and 106 which are threadably embedded in the upper ends of the plungers 101 and 102 and on each of which a suitable lock nut 107 is provided. The vertically movable plungers 101 and 102 are shown as being substantially rectangular or squared in cross-section, however, it is to be understood that these plungers 101 and 102 are or may be of any suitable cross section if so desired.

The upper ends of the plungers 101 and 102 also have stop collars 110 and 111 adjustably secured thereto by screws 112. The vertically disposed first plunger 101 extends downwardly substantially below the lower surface of the lower guide block 96 and past a substantially horizontal leg 115 of a switch actuating member in the form of a bell crank broadly designated at 116. The bell crank 116 is oscillatably mounted as by a shoulder screw 133 on the bracket 91. A vertical leg 117 of the bell crank 116 extends upwardly and has an adjustment screw 120 threadably penetrating the same and which is held in adjusted position by a suitable lock nut 121. The head of this adjustment screw 120 is adapted to at all times engage a plunger 122 of a sensitive switch 123 of any desired construction and which assumes a normally closed position when the plunger 122 is not engaged by the head of the adjustment screw 120 for completing a circuit between a pair of wires or conductors 125 and 126.

The wire or conductor 125 at one side of the switch 123 is connected to one side of a suitable source of electrical energy, not shown, and the wire or conductor 126 at the other side of the switch 123 is connected to one side of a manually operable switch 127 which when closed completes a circuit to the electric motor 25 heretofore described. This electric motor 25 has a conductor or wire 130 extending therefrom to the side of the switch 127 remote from the side to which the wire 126 is connected. A lead wire 131 is also connected to the other side of the motor 25 remote from the side to which the wire 130 is connected and the free end of this wire or conductor 70 is connected to one side of the source of electrical energy not shown, remote from the side to which the wire or conductor 125 is connected.

Thus, upon the plunger 122 of the switch 123 being depressed in a manner to be later described, the circuit to the electric motor will be

opened thus stopping the electric motor 25 and stopping the knitting machine. The upper ends of the adjustment screws 105 and 106 on the upper ends of the respective first and second plungers 101 and 102 are adapted to, at times, be engaged by a substantially L-shaped bunter 134 which may be an integral part of the locking arm 82 and which, in this instance, is suitably secured as by a screw 135, to the locking arm 82. When the roller 81 on the free end of the locking arm 82 is not disposed in one of the notches 76 or 77, the plungers 101 and 102 are each lifted upwardly by a corresponding compression spring 136, the upper end of which bears against a stop pin 137 which penetrates the corresponding plunger and this stop pin 137 resists upward movement of the corresponding plungers 101 and 102 as they engage the lower surface of the upper guide block 95. The lower ends of the compression spring 136 bears against the upper surface of the lower guide block 96.

It will be observed in Figures 4, 5, 6 and 7 that the lower end of the second plunger 102 is pivotally connected, as at 140 to the free end of the horizontal leg 115 of the bell crank 116. The horizontal leg 115 of the bell crank 116 also has an outwardly facing hook projection or portion 141 depending therefrom which is adapted to, at times, be engaged by an upwardly and inwardly facing hook portion 142 of a latch member broadly designated at 143.

The latch member 143 also has a horizontal leg 144 in which one end of a stop pin 145 is fixedly secured as by a pressed fit. This stop pin 145 works in a slotted member 146 which extends downwardly and is suitably secured, as by a screw 147, in a laterally extending arm 150 which is suitably secured, as by rivets 151, in a guide block 152. The guide block 152 is mounted for horizontal sliding movement on a latch guide bar 153 which is suitably secured as by screws 154, to the bracket 91.

The end of the latch member 143, remote from the end on which the hook portion 142, has a downwardly projecting portion 155 integral therewith which is pivotally mounted as at 156, in the bifurcated upper portion of the latch guide block 152. The latch member 143 and its corresponding guide block 152 are normally urged to the left in Figures 4, 5 and 7 by a tension spring 160 which is connected to a suitable spring anchor 161 projecting from the bracket 91 at one end thereof and the other end of this tension spring 160 is connected to an upwardly extending projection or spring anchor 162 which projects upwardly from the shank portion 144 of the latch member 143 above the pivot point 156 and, therefore, not only urges the latch member 143 from right to left in Figure 4 but also normally urges the free end or hook portion 142 of the latch member 143 upwardly to normally cause the stop pin 145 to engage the upper wall of the slot in the slotted member 146.

The lower end of the first plunger 101 is rounded as at 165 and this rounded lower end is adapted to, at times, engage the upper surface of a latch releasing cam or block 166 which is mounted for longitudinal sliding movement on the shank 144 of the latch member 143 and is normally urged against the left-hand surface of either the lower portion of the first plunger 101 or the slotted member 146 by a suitable compression spring 167 which encircles the stem or shank portion 144 of the latch member 143. One end of the compression spring 167 bears against

the downwardly projecting portion 155 of the latch member 143 and the other end thereof bears against the latch releasing cam or block 166.

5 The latch member 143 is shown in inoperative position in Figure 4 and is shown in operative position in Figures 5 and 7. Now, in order to move the latch member 143 from inoperative to operative position, the lower portion of the bracket 91 in Figures 4, 5 and 7 is provided with a notch 170 therein in which a cam or inclined member 171 is adapted to have free movement and this cam member 171 is moved, in a manner to be later described, in such a manner as to engage the outer surface or left-hand surface of a lower portion of the latch guide block 152 which projects below the horizontal plane of the notch 170 in the bracket 91 and to thus move the guide block 152 and the corresponding latch member 143 from the position shown in Figure 4 to the position shown in Figure 5.

20 The latch actuating cam 171 is suitably secured, as by welding, on the free end of a goose-neck portion 172 of a latch actuating lever 173. 25 This latch actuating lever 173 extends downwardly and rearwardly at an angle and is oscillatably mounted as at 174 on the front portion of a latch lever bracket 175 which extends in Figure 1 and is suitably secured, as by screws 30 176, to the medial portion of the outwardly and forwardly extending portion 31 of the upper galley frame 30. The lower portion of the lever 173 has a rearwardly facing reading projection 180 integral therewith which is adapted to, at 35 times, engage the periphery of the segment disk 70 and to, at other times, be engaged by the segments 71 or 72 and against which the reading projection is urged by a suitable tension spring 181 which is connected at one end thereof intermediate the ends of the portion of the lever 173 disposed below the pivot point 174 thereof and the other end of which is suitably secured to an intermediate portion of the lever bracket 175 and which also normally urges the latch actuating lever 173 in a clockwise direction in 40 Figure 1 or in the upper end thereof towards the observer in Figures 4, 5 and 7.

Method of operation

50 During normal operation of the knitting machine shown in Figure 1, such as in knitting the leg portion of a full-fashioned stocking, the roller 81 rests in the notch 76 of the locking cam 75 and, as a result of which, the bunter 134 engages the upper ends of the adjustment screws 105 and 106 on the corresponding plungers 101 and 102 and thus holds them in the position shown in Figure 4 with the various other parts also assuming the position shown in 55 Figure 4. Thus, the adjustment screw 120 on the vertical leg 117 of the bell crank 116 is held out of engagement with the plunger 122 of the switch 123 to permit normal operation of the motor 25, assuming the manually operable switch 127 to be in closed position.

60 Now, the automatic shaft 66 is controlled by conventional means, not shown in the present drawings but as is clearly shown in said Patents Nos. 2,195,872 and 2,432,108, in such a manner as to move the first segment or cam 71 on the segment disk 70 into and out of engagement with the reading projection 180 on the latch actuating lever 173 immediately before a half revolution in rotation is imparted to the welt turner cam shaft 33 and the corresponding locking

cam 75. This occurs immediately preceding the movement of the substantially vertical arm 41 of the welt turner 35 downwardly to where the welt hooks 44 move back of the alternate needles 22 for closing the beards thereon and for transferring the loops from these alternate needles to the welt hooks 44.

Thus, the cam 171 on the upper free end of the latch actuating lever 173 moves forwardly into engagement with the latch guide block 152 to thereby cause the corresponding latch member 143 to move from the position shown in Figure 4 to the position shown in Figure 5. As the latch member 143 moves from left to right to the position shown in Figure 5, the rounded leading edge of the hook projection 142 on the latch member 143 engages the rounded lower edge of the hook projection 141 on the horizontal leg 115 of the bell crank 116 and thus moves downwardly slightly to pass beneath the hook projection 141 and is then moved upwardly by virtue of the tension spring 160 to where the hook portion 142 of the latch member 143 engages the hook projection 141 on the bell crank 116.

It will be observed that as the latch member 143 moves from the position shown in Figure 4 to the position shown in Figure 5, the latch releasing member 166 engages the lower portion of the first plunger 101 before the latch member 143 has been moved to fully operative position.

As movement is subsequently imparted to the locking cam 75, the free end of the locking arm 82 is moved upwardly out of the corresponding notch 76 from the position shown in Figures 4 and 5 to substantially the position shown in Figure 7. Thus, the compression spring 136 will move the plunger 101 upwardly to where the lower end thereof will be disposed above the latch releasing block or cam 166 and, therefore, the compression spring 167 will move the block 166 from the position shown in Figure 5 to the position shown in Figure 7. The second plunger 102 is prevented from moving upwardly because of the latch projection 142 of the latch member 143 being in engagement with the hook portion 141 of the bell crank 116 and, therefore, the motor 25 may continue its operation.

Now, if the operations of the needles 22, the sinkers and the dividers are timed properly relative to the movement of the welt hooks 44 into cooperating position relative to the needles, the cam 72 on the segment disk will move into engagement with the reading projection 180 on the lever 173 immediately before a half revolution of the locking cam 75 is initiated, that is, immediately before the roller on the free end of the locking arm 82 is raised as the notch 76 on the locking cam 75 moves out of engagement therewith.

Now, in the course of a half revolution of the locking cam 75, resulting in the notch 77 moving into engagement with the roller 81 on the free end of the arm 82, and in which position the locking cam 75 remains during the knitting of the welt, the bunter 134 moves upwardly from the position shown in Figures 4 and 5 to the position shown in Figure 7 as heretofore described and then again moves downwardly to return to the position shown in Figure 4. However, at this time, the latch releasing cam or block 166 is disposed below the lower end of the first plunger as shown in Figure 7 and as this plunger is moved downwardly upon the roller 81 dropping into the notch 77, the hook portion 142 of the latch mem-

ber 143 is also moved downwardly to where the hook portion 142 of the latch member 143 will clear the hook portion 141 on the bell crank 116. The tension spring 160 will then cause the latch member 143 to move from right to left or from the position shown in Figure 7 to the position shown in Figure 4 so the various movable parts of the stop motion apparatus 92 will again assume the position shown in Figure 4.

If the welt hooks 44 are moved into operative position in proper timed relation to the corresponding needles 22 following the welt turning operation and before the hooks 44 are elevated to inoperative position, the cam member or segment 72 on the segment disk 70 will then move into engagement with the reading projection 180 on the lever arm 173 to again cause the latch member 143 to be moved from the position shown in Figure 4 to the position shown in Figure 5. Immediately following the movement of this cam member or segment 72 into engagement with the reading projection 180 on the actuating lever 173, the roller 81 will again be raised as the notch 77 in the locking cam 75 moves out of engagement therewith so the various parts will again assume the position shown in Figure 7 to complete a cycle in the normal operation of the stop motion mechanism 92. This will permit continued operation of the electric motor 25.

Now, in the event of the welt hooks 44 moving into operative position in out of time relation to the movement of the needles 22, the corresponding segment or cam 71 or 72 is so positioned that it will fail to engage the reading projection 180 on the lower end of the latch actuating lever 173 while the parts are in the position shown in Figure 4 and before the notch 76 or 77, as the case may be, moves out of engagement with the roller 81 on the free end of the latch arm 82. Consequently, as the free end of the locking arm 82 is elevated, upon one of the notches 76 and 77 in the locking cam 75 moving out of engagement with the roller 81 thereon, the latch member 143 will have remained in the position shown in Figure 4 with the result that the second plunger 102 will be moved upwardly as the first plunger 101 is moved upwardly by virtue of the corresponding compression spring 136 and, thus, the head of the adjustment screw 120 will depress the plunger 122 of the switch 123 and open the switch 123 to thereby stop the motor 25 which will, of course, stop the machine.

The position of the notches 76 and 77 in the locking cam 75 is such that the various other cams, not shown, on the welt turner cam shaft 33 will not impart sufficient movement to the welt hooks 44, upon the locking arm 82 being elevated as the roller 81 moves out of the corresponding notches 76 and 77, sufficiently to break the beards from the corresponding needles 22 or to damage the adjacent sinkers or dividers.

It is thus seen that during normal operation, the L-shaped bunter 134 of the locking arm 82 normally rests upon the upper ends of the adjustment screws 105 and 106 on the corresponding plungers 101 and 102 and, therefore, holds them in a depressed position, as shown in Figure 4, and upon the arm 82 being moved upwardly, only the plunger 101 may move upwardly therewith. Then, as the roller 81 drops into the subsequent notch in the locking cam 75, the first plunger 101 again moves downwardly to release the latch member 143 from the bell crank 116 and then, before the locking arm 82 is again elevated, the latch member 143 is again moved into

engaging position as shown in Figure 5, thus permitting continued operation of the switch mechanism.

It is also seen that in the event of the latch member 143 not being positioned as shown in Figure 5, upon alternate movement of the free end of the locking arm 82, the second plunger 102 will be permitted to move upwardly to thus open the switch 123 and to stop the machine.

There are many reasons why the welt turner cam shaft 33 may not operate in proper timed relation to the needles etc., among which is; the clutch on the main cam shaft, which controls the gear 50, may not operate efficiently or the patterning therefor may be faulty resulting in the welt turner cam shaft 33 turning a fractional part more than a half revolution during operation of the welt turner 35. Also, the gear 50 may adhere slightly to the shaft 26 during other knitting operations, such as operating the picot or narrowing attachments, and such unintentional movement of the welt turner cam shaft 33 would ordinarily damage many intricate parts of the machine, all of which is obviated because the present invention will stop the machine instantly upon a very slight movement of the locking cam 75.

The latch actuating lever 173 may be controlled from sources other than the automatic shaft 66, as is well known to those familiar with this type of knitting machine. This particular shaft 66 is employed in the present arrangement because of its proximity to the welt turner cam shaft 33 and because a step in rotation is imparted to the automatic shaft 66 to reduce the speed of the machine immediately preceding the knitting of the hook-up course and the welt turning course.

In the drawings and specification there has been set forth a preferred embodiment of the invention and although specific terms are employed, they are used in a generic and descriptive sense only and not for purposes of limitation, the scope of the invention being defined in the claims.

I claim:

1. An improvement in a full-fashioned hosiery knitting machine having vertically reciprocable needles and also having a welt turner attachment provided with a plurality of welt hooks adapted to cooperate with said needles in effecting a welt turning operation, said machine also having a welt turner cam shaft for controlling movement of the welt turner into and out of engagement with the needles and also having a locking cam fixed on the welt turner cam shaft provided with a pair of diametrically opposed notches therein and also having a pivoted locking arm provided with a roller on the free end thereof adapted to ride in engagement with the upper surface of said locking cam, said locking cam being so positioned as to cause the roller on said arm to successively drop into either of the notches thereon upon movement of the welt turner attachment into and out of operative position relative to the needles in proper timed relation, said improvement comprising means automatically operable upon failure of the roller on the locking arm moving into the corresponding notch in the locking disk in proper timed relation to movement of the needles for stopping the machine.

2. An improved stop motion apparatus for actuating a switch on a machine having a first arm automatically movable in a reciprocatory manner and said machine also having a second arm movable in a reciprocatory manner in timed relation to the first arm, said stop motion mechanism comprising a bracket having a first and a second mov-

able plunger slidably mounted thereon and each having spring means normally urging the plungers toward the first arm, a switch actuating member pivotally connected to the second plunger and normally being disposed in an inoperative position relative to said switch upon said first arm engaging and depressing the corresponding ends of said plungers, a latch member, means on said switch actuating member adapted to be engaged by said latch member, means on the second arm adapted to move the latch member into engagement with the switch actuating member immediately before the first arm moves out of engagement with the corresponding ends of the plungers and whereby the second plunger will be prevented from moving with said first arm by virtue of said latch member holding the corresponding switch actuating member in a predetermined position, means engageable by the first plunger upon the first plunger being subsequently depressed by said first arm for releasing the latch member from engagement with the switch actuating member, said second arm being operable automatically to subsequently again move said latch member into operative position to permit a repetition of the cycle and whereby, upon failure of said second member moving the latch member into operative position, both of the plungers will be permitted to move with a subsequent movement of the first arm in a direction away from the plungers to thereby permit the switch actuating arm to operate upon said switch.

3. In a machine having a switch-controlled element and also having a first automatically reciprocable member and also having a second automatically reciprocable member adapted to reciprocate in advance of each reciprocation of the first reciprocable member, means for controlling said switch-controlled element comprising a bracket fixed on the machine adjacent said first and second reciprocable members and having a switch thereon connected to the switch-controlled element, a first and second spring loaded plunger normally biased towards the first reciprocable member, means on the second plunger connecting the same with said switch and so arranged that, upon the plungers being engaged and depressed by the first reciprocable member, the switch assumes a predetermined position, means automatically operable by the second reciprocable member in advance of the first reciprocable member moving away from said plungers for holding the second plunger in a predetermined position as the first plunger moves with the first reciprocable member, means engageable by the first plunger upon a subsequent movement of the first reciprocable member toward and in engagement with the plungers for releasing said second plunger from the holding means to cause the second plunger to move with the first plunger upon a subsequent movement of the first reciprocable member away from the plungers in the event that the second reciprocable member does not move in proper timed relation to the first reciprocable member to again cause the second plunger to be held in said predetermined position and whereby, upon failure of the second reciprocable member to operate in proper timed relation to the first reciprocable member, the second plunger will move with the first plunger and the means thereon connecting the same with the switch will cause the switch to assume a different position to thereby effect a change in the switch-controlled element.

4. An improved stop motion mechanism for a

full-fashioned hosiery knitting machine having vertically reciprocable needles and also having a welt turner attachment thereon provided with welt hooks adapted to cooperate with the vertically reciprocable needles in effecting a welt turning operation, said knitting machine having a welt turner cam shaft provided with a locking cam fixed thereon, said locking cam having a pair of diametrically opposed notches in the periphery thereof and said machine also having a locking arm pivotally mounted thereon and being provided with a roller in the free end thereof adapted to ride against the periphery of said locking cam, said machine also having an electric motor for driving the same, said improved stop motion mechanism comprising a bracket disposed adjacent said locking arm and having a switch thereon adapted to be interposed in the circuit between a source of electrical energy and the electric motor, first and second upwardly biased plungers, means on said locking arm normally holding said plungers in a lowered position when the roller on said locking arm is in engagement with either of said diametrically opposed notches in the locking cam, a switch actuating member pivotally connected to the second of said plungers and being held out of engagement with said switch when the plungers are engaged by the means on said locking arm, a latch member disposed adjacent the switch actuating member, cam means adapted to engage the latch member to move the same into operative position relative to the switch member immediately in advance of rotation being imparted to the locking cam for holding the switch actuating lever in inoperative position as the arm is moved upwardly upon the corresponding notch moving out of engagement with the roller on said arm but which will permit the first plunger to move upwardly with said locking arm, means engageable by the first plunger upon the roller on said arm subsequently dropping into another notch in said locking cam for releasing said latch means but resulting in both of the plungers still being held in a lowered position by said arm whereby, upon failure of said cam means to again move the latch means into operative position, upon another step in rotation being imparted to the locking cam, both of the plungers will be permitted to move upwardly with said arm and will thereby permit the switch actuating member to move into engagement with said switch for opening the circuit to said electric motor.

5. An improvement in a machine of a type having a first vertically reciprocable member thereon and also having a second movable member thereon adapted to move in timed relation to movement of the vertically reciprocable member in advance of each upward movement of the vertically reciprocable member, said machine also having a switch controlled element thereon, said improvement comprising a bracket fixed on said machine below said first vertically reciprocable member and having a switch thereon, connections between said switch and the switch controlled element, a switch actuating member movably mounted on said bracket, a first vertically movable plunger and a second vertically movable plunger, spring means normally urging the vertically movable plungers upwardly towards the first vertically reciprocable member, a connection between the second vertically movable plunger and the switch actuating member, said first vertically reciprocable member normally holding the first and the second plungers in a

lowered position and holding the switch actuating member out of operative position relative to said switch, a latch member normally biased to inoperative position relative to the switch actuating member, cam means on said second movable member adapted to move the latch member into operative position for engaging the switch actuating member prior to upward movement of the first vertically reciprocable member, whereby the first reciprocable member will permit the first plunger to move upwardly therewith as it subsequently moves upwardly, means engageable by the first plunger upon a subsequent downward movement of the first vertically reciprocable member for releasing said latch member from the switch actuating member and whereby the first vertically reciprocable member will hold both of the plungers in a lowered position to still prevent the switch from being actuated by the switch actuating member and whereby upon failure of the second movable member to subsequently move the latch member into operative position before the vertically reciprocable member is again moved upwardly, both of the plungers will move upwardly with a subsequent upward movement of the first vertically reciprocable member thus permitting the switch actuating member to operate upon said switch.

6. An improved stop motion mechanism for actuating a switch on a machine having a first arm automatically movable in a reciprocatory manner and said machine also having a second arm movable in a reciprocatory manner in timed relation to the first arm, said stop motion mechanism comprising a bracket having a first and a second movable plunger slidably mounted thereon and each having spring means normally urging the plungers toward the first arm, a switch actuating member pivotally connected to the second plunger and normally being disposed in an inoperative position relative to said switch upon said first arm engaging the corresponding ends of said plunger, a latch member normally biased to inoperative position, a hook on said switch actuating member adapted to be engaged by said latch member, means on the second arm adapted to move the latch member into operative position in engagement with the hook on the switch actuating member immediately before the first arm moves out of engagement with the corresponding ends of the plungers whereby the second plunger will be prevented from moving with said first arm by virtue of said latch member holding the corresponding switch actuating member in a predetermined position, means engageable by the first plunger upon the first plunger being subsequently depressed by said first arm for releasing the latch member from engagement with the hook on the switch actuating member, said second arm being operable automatically to subsequently again move said latch member into operative position to permit a repetition of the cycle and whereby, upon failure of said second member moving the latch member into operative position, both of the plungers will be permitted to move with a subsequent movement of the first arm in a direction away from the plungers to thereby permit the switch actuating arm to operate upon said switch.

7. In a machine having a switch-controlled element and also having a first automatically reciprocable member and also having a second automatically reciprocable member adapted to reciprocate in advance of each reciprocation of the first reciprocable member, means for controlling

said switch-controlled element comprising a bracket fixed on the machine adjacent said first and second reciprocable members and having a switch thereon for controlling the switch-controlled element, a first and a second spring loaded plunger normally biased towards the first reciprocable member, means on the second plunger connecting the same with said switch and so arranged that, upon the plungers being engaged and depressed by the first reciprocable member, the switch assumes a predetermined position, a spring loaded latch member automatically operable by the second reciprocable member in advance of the first reciprocable member moving away from said plungers for holding the second plunger in a predetermined position as the first plunger moves with the first reciprocable member, a block slidably mounted on the latch member, spring means urging said block into engagement with one side of the first plunger as the first plunger moves with the first reciprocable member, said first plunger being movable out of engagement with said block with movement of the first reciprocable member whereby said block will move into alignment with the end of the first plunger to be engaged thereby upon a subsequent movement of the first reciprocable member toward and in engagement with the plungers for releasing said second plunger from the spring loaded latch member to cause the second plunger to move with the first plunger upon a subsequent movement of the first reciprocable member away from the plungers in the event the second reciprocable member does not move in proper timed relation to the first reciprocable member to again cause the second plunger to be held in said predetermined position and whereby, upon failure of the second reciprocable member to operate in proper timed relation to the first reciprocable member, the second plunger will move with the first plunger and the means thereon connecting the same with the switch will cause the switch to assume a different position to thereby effect a change in the switch-controlled element.

8. In a full fashioned hosiery knitting machine having vertically reciprocable needles and also having a welt turner attachment provided with a plurality of welt hooks adapted to cooperate with said needles in effecting a welt turning operation, said machine also having a welt turner cam shaft for controlling movement of the welt turner into and out of engagement with the needles and also having a locking cam fixed on the welt turner cam shaft provided with a pair of spaced irregularities thereon and also having a pivoted locking arm provided with a roller on the free end thereof adapted to ride in engagement with the upper surface of said locking cam, said locking cam being so positioned as to cause the roller on said arm to successively engage the irregularities thereon upon movement of the welt turner attachment into and out of operative position relative to the needles in proper timed relation, means automatically operable upon fail-

ure of the corresponding irregularity on said locking cam moving out of engagement with the roller on the locking arm in proper timed relation to movement of the needles for stopping the machine.

9. In a full fashioned hosiery knitting machine having vertically reciprocable needles and also having a welt turner attachment provided with a plurality of welt hooks adapted to cooperate with said needles in effecting a welt turning operation, said machine also having a welt turner cam shaft for controlling movement of the welt turner into and out of engagement with the needles and also having a locking cam fixed on the welt turner cam shaft provided with at least one irregularity thereon and also having a pivoted locking arm provided with a roller on the free end thereof adapted to ride in engagement with said locking cam, said locking cam being so positioned as to cause the roller on said arm to engage said irregularity thereon upon movement of the welt turner attachment into and out of operative position relative to the needles in proper timed relation, means automatically operable upon said locking cam moving its irregularity beyond said roller during the knitting of a single course, such as the hook-up and welt turning courses of the welt, for stopping the machine.

10. In a full fashioned hosiery knitting machine having vertically reciprocable needles, a welt turner attachment provided with a plurality of welt hooks adapted to cooperate with said needles in effecting a welt turning operation, a welt turner cam shaft for controlling movement of the welt turner into and out of engagement with the needles, a locking cam fixed on the welt turner cam shaft provided with at least one irregularity thereon, a pivoted locking arm provided with means thereon adapted to ride in engagement with said locking cam and said locking cam being so positioned as to cause said means on said pivoted locking arm to engage said irregularity thereon upon movement of the welt turner attachment into and out of operative position relative to the needles in proper timed relation; the combination therewith of means automatically operable upon said locking cam moving its irregularity beyond said means riding on said locking arm, during the knitting of a single predetermined course, for stopping the machine.
